UNITED STATES PATENT OFFICE.

MARTIN J. HEALY, OF CHICAGO, ILLINOIS, ASSIGNOR TO VICTORY MANUFACTURING COMPANY, OF CHICAGO, ILLINOIS, A CORPORATION OF ILLINOIS.

DESIGN FOR A MEMORIAL TABLET.

53,848.

Specification for Design.

Patented Sept. 16, 1919.

Application filed March 13, 1919. Serial No. 282,520. Term of patent 3½ years.

To all whom it may concern:

Be it known that I, MARTIN J. HEALY, a citizen of the United States, residing at Chicago, in the county of Cook and State of Illinois, have invented a new, original, and ornamental Design for a Memorial Tablet, and of which the following is a specification, reference being made to the drawing forming a part thereof.

The figure in the drawing illustrates a face view of a memorial tablet showing my new design.

I claim:

The ornamental design for a memorial tablet as shown.

MARTIN J. HEALY.
